CLAIM

The ornamental design for a workstation partition, as shown and described.

DESCRIPTION

FIG. 1 is a perspective view illustrating my design for a workstation partition;

FIG. 2 is a front elevation view thereof;

FIG. 3 is a right side elevation view thereof;

FIG. 4 is a top plan view thereof;

FIG. 5 is a left side elevation view thereof;

FIG. 6 is a bottom plan view thereof; and,

FIG. 7 is a rear elevation view thereof.

The broken lines in the drawings illustrate environmental subject matter that forms no part of the claimed design.
